LOOSE-LEAF BINDER

Harlow G. Wetmore, Delmar, N.Y., assignor to Buchan
Loose Leaf Records Company, Clifton Heights, Pa.

Filed Apr. 27, 1972, Ser. No. 252,971

Term of patent 14 years

Int. Cl. D19—04

U.S. Cl. D97—1

FIG. 1

FIG. 2

FIG. 3

FIG. 4

FIG. 5

FIG. 6

FIG. 7

FIG. 1 is a side, top and front end perspective view of loose-leaf binder, showing my new design;

FIG. 2 is a top plan view thereof;

FIGS. 3 and 4 are respectively opposite side elevational ws thereof;

FIG. 5 is a bottom plan view thereof;

FIG. 6 is a front end elevational view thereof; and

FIG. 7 is a rear end elevational view thereof.

I claim:

The ornamental design for a loose-leaf binder, as shown.
